UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

EXPANSION JOINT

Application filed July 29, 1926. Serial No. 125,737.

This application is a continuation-in-part of my application Serial No. 336,713, filed November 8, 1919, for air, moisture, and soundproof structures, and method of and material for producing same, and has particular reference to that part of the specification of said application which describes an expansion joint constructed in multiple layers.

10 The primary object of the invention is to construct an expansion joint which will develop an intimate bond with the concrete sections between which it is installed, so as to anchor, so to speak, the joint with the concrete to prevent displacement of the same without sacrificing compressibility and expansibility.

15 In the accompanying drawing which illustrates the preferred construction of the joint, Figure 1 is a perspective view of one form of joint made possible by my invention;

Figure 1^a is a perspective view of the imperforate layer of the joint;

20 Figure 1^b is a perspective view of the perforate layer of the joint;

25 Figure 1^c is a perspective of a modified form;

Figure 1^d is a perspective view of the modification in Figure 1^c with part of the perforated sheet broken away;

30 Figure 2 is a perspective view of a modified form;

Figure 3 is a perspective view of still another form, and

35 Figure 4 is a cross section on the line 4—4 of Figure 1.

It is of course understood that the views show portions of a strip of expansion joint.

Referring to the drawings in detail, 5 represents an intermediate sheet of felt, paper or any other material suitable for the purpose, carrying on opposite sides thereof mastic layers 6 and 7. These layers are preferably developed from bituminous material, although a composition of matter may be used, or in fact any material which will produce a relatively soft mastic mass of an adhesive character.

50 On opposite sides of the layers 6 and 7 are

placed perforated sheets 8 and 9, with perforations 10 therein, as shown.

In applying the sheets 8 and 9 a slight degree of pressure may be used so as to cause the mastic to ooze into the perforations.

55 The sheets 8 and 9 may be produced from any material suitable for the purpose, such as, felt, paper or a composition of different materials.

60 In placing this joint between concrete sections the usual position would be to stand the joint on end and pour the concrete around it.

The concrete in this respect entering the perforations and contacting with the mastic, so that an intimate bond is effected between the concrete and the joint, particularly between the concrete and the mastic part of the joint.

65 After the concrete sets the perforations developed will produce a multiplicity of buttons on the sides of the concrete, which in effect is an interlocking engagement with the joint. With this result I am able to say that the bond between the concrete and the joint is

70 effected by an interlocking engagement as well as by adhesion, since the concrete buttons will adhere to the mastic in the perforations.

75 As a modified form I may simply use two perforated sheets 8 and 9, with an intermediate layer of mastic 6^a. In this form the intermediate sheet 5 is not used.

80 As still another form I may use a relatively thick layer 7^a of mastic between two perforated sheets 8 and 9.

85 In some forms it may also be desirable to use a perforated sheet only on one side of the joint, with an unperforated sheet on an opposite side. This form is illustrated in Figures 1^c and 1^d in which a suitable joint is formed from imperforate sheet 5 and perforate sheet 9 being adhesively or otherwise attached.

90 It can be readily appreciated that where greater thicknesses in the joint are required additional layers may be built up by applying a mastic layer over the perforated sides, and additional perforated sheets over the added mastic layers, or else plain unperforated sheets may be applied to one side. The idea being that, while the relative superimposed relation of the sheets would ordinarily

be arranged as shown, the arrangement may be changed and enlarged upon without departing from the spirit of the invention, as pointed out in the subjoined claims. However, in any arrangement one or both sides of the joint will be surfaced with a perforated sheet in which the mastic partly or completely fills the perforations, so as to bring it in direct contact with the concrete poured around the same.

If desirable the mastic material of the intermediate layers may be mixed with a flow retarder or a fibrous filling material. In the latter case disc like pieces cut out to make the perforations in the sheet 8 and 9 may be used as a filler, either whole or they may be subdivided.

I claim:

1. A multiple layer expansion joint, having one of its sides surfaced with a perforated sheet, with mastic material exposed thru said perforations.
2. A multiple layer expansion joint, having one of its sides surfaced with a perforated sheet, superimposed upon a mastic layer, and with restricted areas of said mastic layer exposed thru said perforations.
3. Expansion joint comprising a strip surfaced with a perforated sheet, with mastic material exposed thru perforations in said sheet.
4. Expansion joint having a multiplicity of perforations in its side, with mastic material exposed thru said perforations.
5. Expansion joint comprising sheets alternating with layers of mastic material, the outside sheets, providing a surface for the joint, being perforated and exposing restricted portions of the mastic layers.

Signed at Chicago, Illinois, this 21st day of July 1926.

ALBERT C. FISCHER.
